E. KOHLER

GAME

Filed May 23, 1923

FIG. 1.

FIG. 2.

INVENTOR

ERNEST KOHLER

BY

Harry C. Schröder

ATTORNEY

UNITED STATES PATENT OFFICE.

ERNEST KOHLER, OF ALAMEDA, CALIFORNIA.

GAME.

Application filed May 23, 1923. Serial No. 640,858.

To all whom it may concern:

Be it known that I, ERNEST KOHLER, a citizen of the United States, residing at Alameda, in the county of Alameda and 5 State of California, have invented certain new and useful Improvements in Games, of which the following is a specification.

My invention is an improved game apparatus, and more particularly of the class 10 in which a ring is connected to a stick by a cord, the object being to catch the ring upon the end of the stick, or upon a peg which is inserted in said stick.

The object of my invention is to provide 15 a game apparatus which is entertaining in use and inexpensive to manufacture.

In the annexed drawing in which my invention is illustrated:

Figure 1 is a perspective view of my improved game apparatus.

Figure 2 is a second perspective view of my apparatus in another position.

Referring more particularly to the drawing, the handle 1 is preferably square in 25 cross section of any desired length, and tapered toward the outer end. A plurality of vari-colored sections 2 are painted upon the stick and are numbered consecutively from the handle end outwardly, the purpose 30 of which will be described later.

The ring 3 is connected to the handle 1 by a cord 4 which is secured to an eye 5 in the tapered end of said handle. The ring 3 is held adjacent the handle and when it 35 is released the player attempts to catch it upon said handle. The section 2 that the ring stops upon indicates the value of the catch. If desired, the ring may be held at an angle to the handle and released and 40 caught as heretofore described, or the ring may be laid upon one side of the stick and

then thrown upwardly and caught as previously described.

A hole 6 is formed in one side of the handle 1 in each of the sections 2 which are 45 adapted to receive a peg 7. This peg may be moved to any one of the holes 6 and the ring 3 caught upon it. The position of the peg in the section indicates the value of the catch. The ring is swung as previously described and then caught upon the peg. When not in use, the peg 7 is kept in a hole 8 in the rear end of the handle 1.

A groove is formed in one face of the handle 1, and a plurality of notches 10 are 55 cut in one edge of said groove. The various notches have various values indicated opposite them and when a marble 11 is rolled in the groove 9 the notch that it stops in will indicate the value of the roll.

Having described my invention, I claim:

1. A game apparatus comprising a handle, a ring, a cord secured to said ring and to the end of said handle, a peg, said handle having a suitable number of holes in the 65 side thereof for the selective reception of said peg, and said handle having a hole for the reception of said peg running longitudinally from the rear end thereof.

2. A game apparatus comprising a handle, 70 substantially square in cross section, a ring, a cord secured to said ring and to the end of said handle, a plurality of sections painted upon said handle, said sections being numbered outwardly from the butt of 75 said handle, said handle having holes therein in each of said sections, and a peg adapted to be selectively placed in any one of said holes.

In testimony whereof I affix my signature.

ERNEST KOHLER.
